UNITED STATES PATENT OFFICE.

WILLIAM A. LORENZ, OF HARTFORD, CONNECTICUT, ASSIGNOR OF ONE-HALF TO BEECH-NUT PACKING COMPANY, OF CANAJOHARIE, NEW YORK, A CORPORATION OF NEW YORK, AND ONE-FOURTH TO WILLIAM H. HONISS, OF HARTFORD, CONNECTICUT.

HERMETIC CLOSURE FOR RECEPTACLES.

No. 889,531.

Specification of Letters Patent.

Patented June 2, 1908.

Application filed August 18, 1906. Serial No. 331,131.

To all whom it may concern:

Be it known that I, WILLIAM A. LORENZ, a citizen of the United States, and resident of Hartford, in the county of Hartford and 5 State of Connecticut, have invented certain new and useful Improvements in Hermetic Closures for Receptacles, of which the following is a full, clear, and exact specification.

This invention relates to improvements in 10 closures for the hermetic sealing of tumblers, and other plain rimmed receptacles. Most of the jars and similar glass receptacles heretofore employed as vacuum packages for food products are provided with a groove or shoulder 15 for receiving the gasket employed for making the air-tight closure joint. When sealed with the wedging type of closure now commonly employed, a tin cap having a flaring flange is pressed down over the outside of 20 the gasket, after the exhausting operation, thereby compressing the gasket downwardly and at an angle against its shoulder or groove upon the receptacle.

It is obviously desirable, to employ for this 25 purpose tumblers or other plain-rimmed receptacles which can be used in the household after being emptied of their original contents, for which uses the aforesaid jars are unfitted because of their gasket receiving grooves and 30 shoulders. It is moreover advantageous in some respects to seat the gasket in the cap or closure, instead of seating it upon the jar, since this facilitates keeping the rim of the jar entirely free and smooth and clean up to 35 the moment of applying the closure, thereby making it easier to see and to remove from the rim any of the material which may be spilled thereon in filling. By thus seating the gasket in the cap instead of on the jar, 40 the gasket itself may also be more easily kept clean, all portions of the joint may be inspected, and its cleanliness assured before placing the closure in position.

The present improved closure consists of a 45 cap having a flexible flaring flange in which a gasket is seated, the flange being provided with an annular shoulder between the top and bottom of the flange, for engaging with the gasket to push the latter downwardly 50 over the rim of the tumbler during the sealing operation.

The form of my improved closure illustrated in the accompanying drawing is suitable for an "outside edge seal," in which the

gasket is wedged at an angle against the outer 55 edge of the tumbler rim. The same principles may, however, be applied to an inside edge seal, in which the gasket is wedged at an angle against the inner edge of the tumbler rim, merely by reversing the flare of the 60 flange, making it flared or coned inwardly instead of outwardly, in which case, however, the gasket would be seated on the outer side of the flange below the shoulder thereof.

Figure 1 is a sectional side view of one side 65 of my improved closure in position for exhausting the air prior to the sealing operation. Fig. 2 is a similar view of the same parts showing them in sealed position. Fig. 3 is a side view in smaller scale, of a sealed 70 tumbler, with one side of its upper portion shown in section. Fig. 4 is a side view, also in section, showing the cap of Fig. 3 with its gasket seated therein before applying it to the tumbler. Fig. 5 is a sectional side view 75 in enlarged scale, showing the closure in its sealed position, and illustrating its adaptability to jars which are oval, or otherwise out of circular contour.

The cap 21 is made of flexible material, 80 preferably sheet metal, and is provided with a comparatively deep flange of a generally flaring contour. The upper portion 22 of the flange is or may be substantially cylindrical. The middle portion 23, separated 85 from the portion 22 by the shoulder 25, is flared, while the lower or edge portion of the flange 24 is or may be approximately cylindrical, or at least turned inwardly from the general angle of the flaring portion 23, so as 90 to conform approximately to the side wall of rim 26 of the tumbler 27. The gasket 30, which is or may be initially of cylindrical band-like form, is seated on the inner side of the flaring flange, so that it is disposed obliquely across the tumbler rim, with its upper edge against the shoulder 25. This gasket 95 is preferably made of a diameter larger than that of the flange, so as to be slightly compressed in placing it in its seat, thereby tending to retain its place by friction, due to its effort to expand toward its original diameter. Or the gasket may be molded or otherwise made approximately to the contour shown in Fig. 1. These gaskets may be placed in 100 their caps at any time prior to the sealing operation, so that the operator in capping the tumblers does not have to handle the

gasket separately as in the instances above referred to wherein the gaskets are seated upon the jars, prior to applying the cap. In fact, with this closure it is unnecessary for the operator to handle the gasket at all. Being thus inserted in and carried by the cap flange, the gaskets and the inner portions of the closure may be kept perfectly clean, and sterilized if desired, it being unnecessary to handle the gasket or any other interior portion of the closure, in placing it upon the filled tumbler.

In sealing tumblers or other plain rimmed receptacles with this closure, the latter is placed upon the tumbler as shown in Fig. 1, the lower portion 24 of the cap flange serving in conjunction with the intervening portion of the gasket 30 to centralize itself with the tumbler, while the flaring portion of the gasket resting upon the tumbler rim supports the closure in a substantially level position during the air exhausting operation, at the close of which the cap is pushed down by a mechanical presser or by means of the readmitted air, to the position shown in Figs. 2, 3 and 5, thereby sealing the tumbler against the readmission of air. As soon as the tumbler is thus sealed and is exposed to the air, the atmospheric pressure continues to force the tumbler and its closure together, thereby compressing the gasket inwardly at an angle against the outer edge of the tumbler rim, and thus forming what is known as an outside wedging closure.

In the commercial manufacture of tumblers and other glass receptacles it is difficult to preserve a truly circular contour of the top of the receptacle, so that many of the tumblers produced by the ordinary commercial methods and even by the best commercial methods are liable to be "out of round." That is to say, they are oval, or flattened at one or more portions of their rims.

Fig. 5 illustrates the adaptability of the present closure to adjust itself to the variations represented by the difference in position between the full line representation 27 and the dot-and-dash line representation 28 of the side wall of a tumbler. This adaptability of the closure to suit these variations in the tumblers is due mainly to the depth of the cap above the shoulder 25, which affords greater amplitude of movement to that portion of the cap flange 31, which bears most directly against the edge of the tumbler rim, this amplitude of movement being illustrated by the difference between the full line and the dot-and-dash line representations of the cap flange.

The enlarged scale in which Fig. 5 is drawn also shows clearly the action of the shoulder 25, in preventing the gasket from being pushed up into the cap above that shoulder, and thereby compelling the gasket to be pushed downwardly over the cap rim.

It also illustrates clearly the action of the shoulder in turning or wrapping the gasket inwardly over the top edge of the tumbler, thereby adding to the security of the outer edge seal the further security due to that wrapping.

It is not essential that the upper zone 22 of the cap flange shall be more than approximately cylindrical. The vertical length of this zone, rather than its inclination is the chief factor in its usefulness. Where, however, the other portions of the flange are properly proportioned to the tumbler, I consider that the cylinder form better enables the closure to conform to the ordinary distortions and variations of the tumblers.

I claim as my invention:

1. The combination with a tumbler, of a wedging closure, comprising a gasket, a cap having a flexible flaring flange provided with an internal annular shoulder integral with the flange between the top and bottom of the flange for engaging with the gasket to push the gasket downward with the cap during the sealing operation.

2. The combination with a tumbler, of a wedging closure comprising a gasket disposed obliquely across the tumbler rim, a cap having a flexible flaring flange for wedging the gasket against the tumbler rim, provided with an internal annular shoulder integral with the flange and disposed between the top and bottom of the flange to prevent the gasket from being pushed above the said shoulder.

3. The combination with a tumbler, of a wedging closure, comprising a gasket, a cap having a flexible flange the upper portion of which is substantially cylindrical and the lower portion of which is flaring, the flange being provided with an integral annular shoulder between said cylindrical and flaring portions to prevent the gasket from being pushed above the said shoulder.

4. The combination with a tumbler, of a wedging closure comprising a gasket disposed obliquely across the tumbler rim, a cap having a flexible flange, the upper portion of which is substantially cylindrical, and the lower portion of which is flaring to receive the gasket, the flange being provided with an integral annular shoulder between the said cylindrical and flaring portions for engaging with the gasket to push it down with the cap.

5. A closure for tumblers and plain rimmed receptacles, comprising a cap provided with a flexible flange, having its upper portion substantially cylindrical, and having its lower portion flared downwardly and outwardly, the flange being also provided with a substantially horizontal annular shoulder lying approximately between the said flaring and cylindrical portions, and a gasket seated in the flaring portion below the said shoulder.

6. A closure for tumblers and plain rimmed receptacles, comprising a cap provided with a flexible flange, having its upper portion substantially cylindrical, and having its lower portion flared downwardly and outwardly, the flange being also provided with a substantially horizontal annular shoulder lying approximately between the said flaring and cylindrical portions, and a flaring band-shaped gasket seated in the flaring portion of

the flange, with its upper edge underlying the said shoulder.

In testimony whereof, I have signed my name to this specification in the presence of two subscribing witnesses this 23rd day of 15 July, 1906.
